ABSTRACT

Apparatuses and systems for analog/digital input architecture having programmable analog output mode are described herein. One apparatus includes a current source component to create a current source, a pulse-width modulation (PWM) control component to implement an analog output mode, wherein the analog output mode is implemented on a same input/output terminal as at least one other device mode, a dither input component to receive a dither signal, a current shunt component to create an input shunt, a resistance/thermistor input pull-up component to provide an excitation voltage, a voltage/current input scaling component to provide input prescaling, an input protection component to protect at least one port of the apparatus from damage, and an input filter component to provide filtering to high frequency noise.

Fig. 3

ANALOG/DIGITAL INPUT ARCHITECTURE HAVING PROGRAMMABLE ANALOG OUTPUT MODE

TECHNICAL FIELD

The present disclosure relates to apparatuses and systems for analog/digital input architecture having programmable analog output mode.

BACKGROUND

Buildings may contain building systems. One such system, for example, is a large scale refrigeration system. In a refrigeration system, one or more rooms (commonly referred to as "refrigeration racks") can contain compressors, fans, and/or associated control circuitry (e.g., control modules). Refrigeration racks may be custom built to customer specifications by a designer and/or manufacturer.

Previous control modules may have taken advantage of once-larger refrigeration racks having surplus space. With less of a premium placed on space, previous control modules could provide reduced (e.g., one or two) functions per module (e.g., relay outputs, analog outputs, and digital and/or analog outputs).

As physical space provided for control modules continues to become more limited, previous control modules may be rendered too large for installation. An installer and/or designer may find inadequate space in a refrigeration rack to install a number of previous control modules that have a desired mix of fixed input/output functions under previous approaches.

BRIEF DESCRIPTION OF THE DRAWINGS

FIG. 1 illustrates an apparatus including analog/digital input architecture having programmable analog output mode in accordance with one or more embodiments of the present disclosure.

FIG. 2 illustrates a dual channel apparatus including analog/digital input architecture having programmable analog output mode in accordance with one or more embodiments of the present disclosure.

FIG. 3 illustrates a system including operating analog/digital input architecture having programmable analog output mode in accordance with one or more embodiments of the present disclosure.

DETAILED DESCRIPTION

Apparatuses and systems for analog/digital input architecture having programmable analog output mode are described herein. For example, one or more embodiments include a current source component to create a current source, a pulse-width modulation (PWM) control component to implement an analog output mode, wherein the analog output mode is implemented on a same input/output terminal as at least one other device mode, a dither input component to receive a dither signal, a current shunt component to create an input shunt, a resistance/thermistor input pull-up component to provide an excitation voltage, a voltage/current input scaling component to provide input prescaling, an input protection component to protect at least one port of the apparatus from damage, and an input filter component to provide filtering to high frequency noise.

Embodiments of the present disclosure can minimize a number of fixed function input/output (I/O) points by pro-

viding a flexible yet easily configurable architecture that allows multiple I/O types and modes of operation on the same terminal (e.g., pin). To do so, embodiments of the present disclosure can combine an analog output mode with input architecture. Embodiments herein can be employed in refrigeration contexts and/or elsewhere. Some embodiments can control a refrigeration system and/or a heating, ventilation, and air conditioning (HVAC) system, for instance.

Various universal input structures that embody previous approaches may make use of an increasing number of I/O port pins and high resolution analog/digital inputs available in controllers (e.g., microcontrollers). Typically, port pins can be arranged to control the various modes of operation of the input. Through executable instructions (e.g., software), analog inputs can be used for analog and/or digital inputs, while the I/O port pins enable pull-up resistors for resistance measurements, divider circuits for voltage and/or digital measurements, and, through the use of ultra low-on resistance metal-oxide-semiconductor field-effect transistors (MOSFETs), enable shunt resistors for current measurement.

However, previous approaches are met with drawbacks. For example, in digital input modes, the use of the resistance measurement pull up for dry contact type inputs may provide merely micro amps of wetting current (e.g., approximately 300 micro amps). As a result, measurement reliability may be compromised when certain (e.g., inferior) contact material is used for the input source, such as in inexpensive door switches, for instance. Additionally, the digital input open circuit voltage in previous approaches may be fixed at the level of pull-up supply voltage (e.g., 3.3 volts). Further, the lack of an analog output mode may result in the inclusion of additional fixed function outputs, which may increase the overall control module size and/or cost, or which may impel the use of additional fixed function control modules to be added to a control system.

Embodiments of the present disclosure can leverage one or more integrated timer counter functions multiplexed on controller I/O port pins to include a pulse width modulated (PWM) analog output mode in the input architecture of the controller. Accordingly, input enhancements can be realized with a reduction in the increase of cost and/or size. For example, embodiments of the present disclosure can provide a precision closed loop (e.g., 0V-10V) analog output mode; approximately 10 millamps of wetting current for digital and/or dry contact type inputs; adjustable open circuit voltage for digital and/or dry contact digital inputs; and/or adjustable DC level for use with digital solid state relays.

The programmable analog output mode, in accordance with one or more embodiments described herein, can be implemented using a PWM signal. The PWM signal can be programmed using a frequency and/or pulse width that allows filtering components to provide a voltage output with reduced (e.g., minimal) ripple. The programmable analog output mode can be run in a calibrated open loop mode and/or can use proportional-integral-derivative (PID) loop control with voltage feedback, for instance. In some embodiments, the voltage mode of the input can be used for feedback in PID loop control.

In some embodiments, the output voltage can be a continuously variable output (e.g., from 0V-10V). In some embodiments, the output voltage can be used for other applications, such as driving a solid state relay, for instance, using two output levels (e.g., 0V and 5V).

The analog output mode can be implemented without manual hardware configuration. In some embodiments, the

PWM output from the controller, when driven to an "off" state, can allow the analog input to function normally.

In the following detailed description, reference is made to the accompanying drawings that form a part hereof. The drawings show by way of illustration how one or more embodiments of the disclosure may be practiced.

These embodiments are described in sufficient detail to enable those of ordinary skill in the art to practice one or more embodiments of this disclosure. It is to be understood that other embodiments may be utilized and that process changes may be made without departing from the scope of the present disclosure.

As will be appreciated, elements shown in the various embodiments herein can be added, exchanged, combined, and/or eliminated so as to provide a number of additional embodiments of the present disclosure. The proportion and the relative scale of the elements provided in the figures are intended to illustrate the embodiments of the present disclosure, and should not be taken in a limiting sense.

The figures herein follow a numbering convention in which the first digit or digits correspond to the drawing figure number and the remaining digits identify an element or component in the drawing. Similar elements or components between different figures may be identified by the use of similar digits.

As used herein, "a" or "a number of" something can refer to one or more such things. For example, "a number of blocks" can refer to one or more blocks.

FIG. 1 illustrates an apparatus 100 including analog/digital input architecture having programmable analog output mode in accordance with one or more embodiments of the present disclosure. The apparatus 100 can be (or be a portion of) a controller (e.g., a microcontroller), for instance. The apparatus 100 can be implemented on a printed circuit board (PCB), though embodiments of the present disclosure are not so limited. The apparatus 100 can be one half of a block containing two complete universal inputs, for instance. That is, in some embodiments, the apparatus 100 can represent one channel of a dual channel block.

The apparatus 100 can include a current source component 102. The current source component 102 can include one or more resistors, transistors, and/or diodes configured to create a current source (e.g., a simple current source). The current source can be used to limit an analog output maximum drive current and/or a digital input wetting current. In the embodiment illustrated in FIG. 1, the current source component 102 includes a current set resistor R24, which can set the output current to approximately 30 milliamps. Due to increased dissipation of transistor Q3 at this current, a low saturation transistor can be used to increase the dissipation capability of R24. In some embodiments, the maximum current can be set to approximately 12 milliamps (by a resistance of R24 being 40.2 Ohms) thereby reducing (e.g., minimizing) the maximum dissipation of the transistor Q3 and allowing a less expensive transistor to be used.

The apparatus 100 can include a PWM control component 104. The PWM control component 104 can implement the analog output mode (discussed further below). The PWM control component 104 can provide a voltage gain to the 1 KHz PWM output of the apparatus (PWM_CTLA) through transistor Q5 and resistor R27, for instance. A two pole passive filter comprised of resistors R17, R25, capacitors C5 and C6 can provide a frequency roll-off of approximately -6 db at 10 Hz. A Darlington transistor Q7 can provide gain to the high impedance post filter DC signal. The full scale

range of the output can be determined by the supply rail (VDD_AOUT) and transistor Q5 pull up supply (V+_PU_A).

The apparatus 100 can include a dither input component 106. The dither input component 106 can receive a dither signal (AI_DITHER) (e.g., 50 Hz at 50% duty cycle) through resistor R15. The dither signal can be used in one or more (e.g., all) universal input (UI) modes of operation. When implemented with software oversampling, an increase in analog-to-digital (A/D) resolution can be obtained. In cases where dither is not desired, the port pin (e.g., one of a plurality of port pins) of the apparatus can be set to a high impedance state, for instance, to prevent loading of the measurement system.

The apparatus 100 can include a current shunt component 108. The current shunt component 108 can create an input shunt, for instance. When on, low $R_{DS(ON)}$ field-effect transistor Q1 can provide 5 Ohms (e.g., a maximum of 5 Ohms) series resistance to parallel resistors R7, R8, R9, and R10, thereby creating an approximately 525 Ohm input shunt. In cases where current input mode is selected, the current shunt component 108 can be switched on by a processor signal (CURR_CTLA). For example, the current shunt component 108 can convert an input signal of 4 to 20 milliamps to approximately 2 to 10 V (DC). The current shunt component 108 can be sized to 2 W allowing a continuous application of 28V AC to the input terminals without damage to the apparatus 100. During a reset of the apparatus 100, a gate resistor R21 can hold transistor Q1 off, for instance.

The apparatus 100 can include a resistance/thermistor input pull-up component 110 (hereinafter "pull-up component 110"). Pull-up component 110 can provide an excitation voltage for a thermistor and/or for general purpose resistance input measurements. A source voltage for the pull-up component 110 can be derived from control pin PULLUP_CTLINA, for instance, and can be set at a particular (e.g., high) level when resistance or thermistor mode is selected. In some embodiments, the source voltage can be set to approximately 3.3 V when resistance or thermistor mode is selected. To provide ratio metric performance of the analog input, the power supply for the apparatus 100 can be derived from a same regulator used as the A/D voltage reference. During voltage, current, and/or digital modes, PULLUP_CTLINA can be set to a high impedance state to prevent the pin from inducing measurement errors. In cases where the input is used as the analog output, the signal can be set to logic 0 and can provide a minimum load for the output (e.g., to allow conduction of diode D7 when the output is driving high impedance inputs).

The apparatus 100 can include a voltage/current input scaling component 112. The voltage/current input scaling component 112 can include resistors R1 and R3, for instance, configured as an input prescaler (e.g., that provides input prescaling) when the universal input is in voltage, current, analog output, and/or digital input modes. The prescaler can be enabled by setting UI control signal DIVIDER_CTLINA to logic 0 (e.g., approximately 0 V DC), which completes the circuit of the R1/R3 voltage divider. Full scale voltages up to 11.12 V may be measured by the analog input when a 3.3 V reference is used by the A/D. In cases where the input is placed in resistance/thermistor mode, the prescaler can be disabled by placing DIVIDER_CTLINA in a high impedance state.

The apparatus 100 can include an input protection component 114. The input protection component 114 can include a plurality of diodes, resistors, and/or transistors (e.g., a substrate diode portion), which can protect at least one port

(e.g., the universal input and port(s)) of the apparatus **100** from damage under continuous application of 28 V AC and/or transient application in excess of 28 V AC. Diodes D1 and D2 can divert voltages greater than nominal +4 V to VDD_3V3 and negative voltages to ground. Substrate diode portion Q1 can divert negative current (e.g., AC input from wiring error) to ground. Resistor R1 can be employed as a current limiter, for instance.

The apparatus **100** can include an input filter component **116**. The input filter component can provide filtering to high frequency noise and/or transients (e.g., via C1 (0.068 μ F/100 V)). That is, the input filter component **116** can filter out high frequency noise and/or transients. In some embodiments, the input filter component **116** can include an additional capacitor (e.g., C3 (0.47 μ F)) to provide filtering to frequencies above 20 Hz (e.g., a digital pulse counting limit).

FIG. 2 illustrates a dual channel apparatus **218** including analog/digital input architecture having programmable analog output mode in accordance with one or more embodiments of the present disclosure. The apparatus **218** can contain two universal inputs, for instance. That is, in some embodiments, the apparatus **100** can include both channels of a dual channel block.

As shown in FIG. 2, the apparatus **218** includes two portions, each analogous to the apparatus **100**, previously described in connection with FIG. 1. For instance, each portion includes a current source component **202**, a PWM control component **204**, a dither input component **206**, a current shunt component **208**, a pull-up component **210**, a voltage/current input scaling component **212**, an input protection component **214**, and an input filter component **216**. For purposes of clarity, only one of the portions (channels) of the apparatus **218** is accompanied by reference numerals in FIG. 2.

As previously discussed, the dual channel apparatus **218** can be formed on a substrate (e.g., a PCB). In some embodiments, a width of the dual channel apparatus **218** can be approximately 0.75 inches (e.g., 0.74-0.76 inches). In some embodiments, a length of the dual channel apparatus **218** can be approximately 2.15 inches (e.g., 2.14-2.16 inches). In some embodiments, a PCB can include a plurality of dual channel apparatuses **218**. For example, a PCB having a width of 5 inches and a length of 7 inches can include 8 dual channel apparatuses **218**.

FIG. 3 illustrates a system **320** including operating analog/digital input architecture having programmable analog output mode in accordance with one or more embodiments of the present disclosure. System **320** includes a computing device **322**. Computing device **322** can be, for example, a laptop computer, a desktop computer, or a mobile device (e.g., a mobile phone, a personal digital assistant, etc.), among other types of computing devices.

As shown in FIG. 3, computing device **322** includes a memory **326** and a processor **324** coupled to memory **326**. Memory **326** can be any type of storage medium that can be accessed by processor **324** to perform various examples of the present disclosure. For example, memory **326** can be a non-transitory computer readable medium having computer readable instructions (e.g., computer program instructions) stored thereon that are executable by processor **324** to operate input circuitry with programmable analog output in accordance with one or more embodiments of the present disclosure.

Memory **326** can be volatile or nonvolatile memory. Memory **326** can also be removable (e.g., portable) memory, or non-removable (e.g., internal) memory. For example, memory **326** can be random access memory (RAM) (e.g.,

dynamic random access memory (DRAM) and/or phase change random access memory (PCRAM)), read-only memory (ROM) (e.g., electrically erasable programmable read-only memory (EEPROM) and/or compact-disc read-only memory (CD-ROM)), flash memory, a laser disc, a digital versatile disc (DVD) or other optical disk storage, and/or a magnetic medium such as magnetic cassettes, tapes, or disks, among other types of memory.

Further, although memory **326** is illustrated as being located in computing device **322**, embodiments of the present disclosure are not so limited. For example, memory **326** can also be located internal to another computing resource (e.g., enabling computer readable instructions to be downloaded over the Internet or another wired or wireless connection).

In addition to, or in place of, the execution of executable instructions, various examples of the present disclosure can be performed via one or more devices (e.g., one or more controllers) having logic. As used herein, “logic” is an alternative or additional processing resource to execute the actions and/or functions, etc., described herein, which includes hardware (e.g., various forms of transistor logic, application specific integrated circuits (ASICs), etc.), as opposed to computer executable instructions (e.g., software, firmware, etc.) stored in memory and executable by a processor. It is presumed that logic similarly executes instructions for purposes of the embodiments of the present disclosure.

The computing device **322** can communicate with a plurality of components of an apparatus **300**. The computing device **322** can be local with respect to the apparatus **300**, for instance. The computing device **322** can be remote with respect to the apparatus **300**, for instance. In some embodiments, the components may be analogous to the components discussed in connection with FIGS. 1 and/or 2; in some embodiments, the apparatus **300** may be analogous to the apparatus **100** and/or the apparatus **200** respectively discussed in connection with FIGS. 1 and/or 2. That is, the components of system **320** can include a current source component **302**, a PWM control component **304**, a dither input component **306**, a current shunt component **308**, a pull-up component **310**, a voltage/current input scaling component **312**, an input protection component **314**, and/or an input filter component **316** (cumulatively referred to as “components **302-316**”).

The apparatus **300** (which can be defined by the components **302-316**) can enter a plurality of modes. In some embodiments, the plurality of modes can include, for example, a current mode, a resistance mode, a voltage mode, a digital/pulse counting mode, and/or an analog output mode. The memory **326** can include instructions executable by the processor **324** to cause the apparatus to enter a particular mode of a plurality of modes by causing a modification of an operation of at least one of the components **302-316**.

In the current mode, the apparatus **300** can be configured to determine (e.g., detect, measure, acquire, etc.) a current. To enter the current mode, the memory **326** can include instructions executable by the processor **324** to set a logic level of the current shunt component **308** to high via a CURR_CTLA control line connected to the current shunt component **308**. The memory **326** can include instructions executable by the processor **324** to set a logic level of the voltage/current input scaling module **312** to low via a DIVIDER_CTLINA control line connected to the voltage/current input scaling module **312**. The memory **326** can include instructions executable by the processor **324** to set a

duty cycle of the PWM control module 304 to a lowest setting (e.g., minimum) via a PWM_CTLA control line connected to the PWM control module 304. The memory 326 can include instructions executable by the processor 324 to set a logic level of the pull-up component 310 to highZ via a PULLUP_CTL_INA control line connected to the pull-up component 310.

By way of example and not limitation, the below table illustrates further details associated with the current mode.

Minimum Measurable Range	3.5 ma to 20.5 ma
Accuracy	Not less than +/-1% of span
Resolution	Not less than 16 uA/bit
Compliance	Input shall support current loop devices having a loop compliance of 10 V or less
Total Input Impedance	523 ohms (+/-10%)

In the resistance mode, the apparatus 300 can be configured to determine a resistance. To enter the resistance mode, the memory 326 can include instructions executable by the processor 324 to set a logic level of the current shunt component 308 to low via a CURR_CTLA control line connected to the current shunt component 308. The memory 326 can include instructions executable by the processor 324 to set a logic level of the voltage/current input scaling module 312 to highZ via a DIVIDER_CTL_INA control line connected to the voltage/current input scaling module 312. The memory 326 can include instructions executable by the processor 324 to set a duty cycle of the PWM control module 304 to a lowest setting (e.g., minimum) via a PWM_CTLA control line connected to the PWM control module 304. The memory 326 can include instructions executable by the processor 324 to set a logic level of the pull-up component 310 to high via a PULLUP_CTL_INA control line connected to the pull-up component 310.

By way of example and not limitation, the below table illustrates further details associated with the resistance mode.

Operating Range	100 ohms to 100K ohms
Accuracy	2% of Reading
Precision (max.)	100-1K, 0.5 ohms 1K-10K, 4 ohms 10K-50K, 50 ohms 50K-100K, 350 ohms
Out of Range Detection	Outside the range 100-100K ohms
Thermal Drift	0.02% per C. (-20 C.-60 C.)

In the voltage mode, the apparatus 300 can be configured to determine a voltage. To enter the voltage mode, the memory 326 can include instructions executable by the processor 324 to set a logic level of the current shunt component 308 to low via a CURR_CTLA control line connected to the current shunt component 308. The memory 326 can include instructions executable by the processor 324 to set a logic level of the voltage/current input scaling module 312 to low via a DIVIDER_CTL_INA control line connected to the voltage/current input scaling module 312. The memory 326 can include instructions executable by the processor 324 to set a duty cycle of the PWM control module 304 to a lowest setting (e.g., minimum) via a PWM_CTLA control line connected to the PWM control module 304. The memory 326 can include instructions executable by the processor 324 to set a logic level of the pull-up component 310 to highZ via a PULLUP_CTL_INA control line connected to the pull-up component 310.

By way of example and not limitation, the below table illustrates further details associated with the voltage mode.

5	Minimum Measurable Range	0.5 to 10.5 VDC
	Accuracy	Not less than +/-2% of span
	Resolution	Not less than 10 mV/bit
	Total Input Impedance	>10K ohms

10 In the digital/pulse counting mode, the apparatus 300 can be configured to determine a number of pulses received over a particular period of time, for instance. To enter the digital/pulse counting mode, the memory 326 can include instructions executable by the processor 324 to set a logic level of the current shunt component 308 to low via a CURR_CTLA control line connected to the current shunt component 308. The memory 326 can include instructions executable by the processor 324 to set a logic level of the voltage/current input scaling module 312 to low via a DIVIDER_CTL_INA control line connected to the voltage/current input scaling module 312. The memory 326 can include instructions executable by the processor 324 to set a duty cycle of the PWM control module 304 to a particular percentage (e.g., between 0% and 100%) based on a determined wetting voltage via a PWM_CTLA control line connected to the PWM control module 304. The memory 326 can include instructions executable by the processor 324 to set a logic level of the pull-up component 310 to highZ via a PULLUP_CTL_INA control line connected to the pull-up component 310.

15 20 25 30 By way of example and not limitation, the below table illustrates further details associated with the digital/pulse counting mode.

35	Maximum Measurable Frequency	20 Hz (50% duty cycle)
	Open Circuit Voltage	Programmable (3.3-10 V)
	Wetting Current	Input shall have a dry contact wetting current of not less than 10 mA
	Total Input Impedance	>10K ohms
	Counter capability	32 bits

40 45 50 55 In the analog output mode, the apparatus 300 can be configured to provide an analog output. To enter the analog output mode, the memory 326 can include instructions executable by the processor 324 to set a logic level of the current shunt component 308 to low via a CURR_CTLA control line connected to the current shunt component 308. The memory 326 can include instructions executable by the processor 324 to set a logic level of the voltage/current input scaling module 312 to low via a DIVIDER_CTL_INA control line connected to the voltage/current input scaling module 312. The memory 326 can include instructions executable by the processor 324 to set a duty cycle of the PWM control module 304 to a particular percentage (e.g., between 0% and 100%) based on an analog output set point via a PWM_CTLA control line connected to the PWM control module 304. The memory 326 can include instructions executable by the processor 324 to set a logic level of the pull-up component 310 to low via a PULLUP_CTL_INA control line connected to the pull-up component 310.

60 By way of example and not limitation, the below table illustrates further details associated with the analog output mode.

65	Minimum Output Range	0.1 to 10.5 VDC
	Accuracy	Not less than +/-2% of span

Resolution	Not greater than 100 mV/bit
Load Impedance	>1K ohms
Maximum Source Current	Not less than 10 mA

In some embodiments, control lines associated with other aspects of the apparatus 300 (e.g., other components) can be held constant, for instance. For example a control line associated with the input protection component 314 (VDD_3V3) can be set at a particular supply voltage (e.g., +3.3 V DC). A control line associated with the current source component 302 (VDD_AOUT) can be set at a particular supply voltage (e.g., +15 V DC). A control line associated with a pull-up supply can be set at a particular supply voltage (e.g., +15 V DC). A control line associated with the dither input component 306 can be set at a particular signal input (e.g., 50 Hz at 50% duty cycle). A control line associated with an analog input point can be set at a particular number of bits (e.g., effective number of bits), such as 10 bits, for instance.

Although specific embodiments have been illustrated and described herein, those of ordinary skill in the art will appreciate that any arrangement calculated to achieve the same techniques can be substituted for the specific embodiments shown. This disclosure is intended to cover any and all adaptations or variations of various embodiments of the disclosure.

It is to be understood that the above description has been made in an illustrative fashion, and not a restrictive one. Combination of the above embodiments, and other embodiments not specifically described herein will be apparent to those of skill in the art upon reviewing the above description.

The scope of the various embodiments of the disclosure includes any other applications in which the above structures and methods are used. Therefore, the scope of various embodiments of the disclosure should be determined with reference to the appended claims, along with the full range of equivalents to which such claims are entitled.

In the foregoing Detailed Description, various features are grouped together in example embodiments illustrated in the figures for the purpose of streamlining the disclosure. This method of disclosure is not to be interpreted as reflecting an intention that the embodiments of the disclosure require more features than are expressly recited in each claim.

Rather, as the following claims reflect, inventive subject matter lies in less than all features of a single disclosed embodiment. Thus, the following claims are hereby incorporated into the Detailed Description, with each claim standing on its own as a separate embodiment.

What is claimed:

1. An apparatus, comprising:
input filter circuitry connected to an input terminal of the apparatus to provide filtering to an input signal;
current shunt circuitry connected to the input filter circuitry to create an input shunt while the apparatus is operating in a current mode to determine a current associated with the input signal;
input protection circuitry connected to the current shunt circuitry to protect the input terminal from damage;
resistance/thermistor input pull-up circuitry connected to the current shunt circuitry to provide an excitation voltage while the apparatus is operating in a resistance mode to determine a resistance associated with the input signal;

voltage/current input scaling circuitry connected to the resistance/thermistor input pull-up circuitry to provide input prescaling while the apparatus is operating in a voltage mode to determine a voltage associated with the input signal, an analog output mode to provide an analog output, a digital/pulse counting mode to determine a number of pulses received at the input terminal over a particular period of time, and the current mode; dither input circuitry connected to the voltage/current input scaling circuitry to receive a dither signal; pulse-width modulation (PWM) control circuitry to provide a voltage gain to the analog output while the apparatus is operating in the analog output mode; and current source circuitry to create a current source to limit a current of the analog output while the apparatus is operating in the analog output mode and to limit a wetting current while the apparatus is operating in the digital/pulse counting mode.

2. The apparatus of claim 1, wherein the apparatus is configured to control a refrigeration system.

3. The apparatus of claim 1, wherein the current shunt circuitry is configured to allow a continuous application of 28V AC to an input terminal of the apparatus without damage to the apparatus.

4. The apparatus of claim 1, wherein the analog output mode is run in a calibrated open loop mode.

5. The apparatus of claim 1, wherein the analog output mode is run using proportional-integral-derivative (PID) loop control with voltage feedback.

6. An apparatus, comprising:
a substrate; and
a dual channel apparatus on the substrate, the dual channel apparatus including:
input filter circuitry connected to an input terminal of the apparatus to provide filtering to an input signal;

current shunt circuitry connected to the input filter circuitry to create an input shunt while the apparatus is operating in a current mode to determine a current associated with the input signal;
input protection circuitry connected to the current shunt circuitry to protect the input terminal from damage;
resistance/thermistor input pull-up circuitry connected to the current shunt circuitry to provide an excitation voltage while the apparatus is operating in a resistance mode to determine a resistance associated with the input signal;

voltage/current input scaling circuitry connected to the resistance/thermistor input pull-up circuitry to provide input prescaling while the apparatus is operating in a voltage mode to determine a voltage associated with the input signal, an analog output mode to provide an analog output, a digital/pulse counting mode to determine a number of pulses received at the input terminal over a particular period of time, and the current mode;

dither input circuitry connected to the voltage/current input scaling circuitry to receive a dither signal; pulse-width modulation (PWM) control circuitry connected to the input protection circuitry to provide a voltage gain to the analog output while the apparatus is operating in the analog output mode; and current source circuitry connected to the PWM control circuitry to create a current source to limit a current of the analog output while the apparatus is operating in the analog output mode and to limit a wetting current while the apparatus is operating in the digital/pulse counting mode;

11

wherein the apparatus is configured to be disposed in a refrigeration rack and is configured to control a refrigeration system.

7. The apparatus of claim 6, wherein a width of the dual channel apparatus is between 0.74 and 0.76 inches, and wherein a length of the dual channel apparatus is between 2.14 and 2.16 inches. 5

8. The apparatus of claim 6, wherein the apparatus includes a plurality of dual channel apparatuses on the substrate.

9. The apparatus of claim 8, wherein the apparatus includes 8 dual channel apparatuses on the substrate, and wherein a width of the substrate does not exceed 5 inches and a length of the substrate does not exceed 7 inches.

10. A system, comprising:

an apparatus, including:

current source circuitry, pulse-width modulation (PWM) control circuitry, dither input circuitry, current shunt circuitry, resistance/thermistor input pull-up circuitry, voltage/current input scaling circuitry, input protection circuitry, and input filter circuitry; a memory; and

a processor configured to execute executable instructions stored in the memory to:

cause the apparatus to enable a particular mode of a plurality of modes by causing a modification of an operation of at least one of the current source circuitry, pulse-width modulation (PWM) control circuitry, dither input circuitry, current shunt circuitry, resistance/thermistor input pull-up circuitry, voltage/

current input scaling circuitry, input protection circuitry, and input filter circuitry, wherein: the input filter circuitry is connected to an input terminal of the apparatus and configured to provide filtering to an input signal;

the current shunt circuitry is connected to the input filter circuitry and configured to create an input shunt while the apparatus is operating in a current mode to determine a current associated with the input signal;

the input protection circuitry is connected to the current shunt circuitry and configured to protect the input terminal from damage;

the resistance/thermistor input pull-up circuitry is connected to the current shunt circuitry and configured to provide an excitation voltage while the apparatus is operating in a resistance mode to determine a resistance associated with the input signal;

the voltage/current input scaling circuitry is connected to the resistance/thermistor input pull-up circuitry and configured to provide input prescaling while the apparatus is operating in a voltage mode to determine a voltage associated with the input signal, an analog output mode to provide an analog output, a digital/pulse counting mode to determine a number of pulses received at the input terminal over a particular period of time, and the current mode;

the dither input circuitry is connected to the voltage/ current input scaling circuitry and configured to receive a dither signal;

the pulse-width modulation (PWM) control circuitry is connected to the input protection circuitry and configured to provide a voltage gain to the analog output while the apparatus is operating in the analog output mode; and

12

the current source circuitry is connected to the PWM control circuitry and configured to create a current source to limit a current of the analog output while the apparatus is operating in the analog output mode and to limit a wetting current while the apparatus is operating in the digital/pulse counting mode.

11. The system of claim 10, wherein the processor is configured to execute instructions stored in the memory to cause the apparatus to enable the current mode, and wherein enabling the current mode includes:

setting a logic level of the current shunt circuitry to high; setting a logic level of the voltage/current input scaling circuitry to low; setting a duty cycle of the PWM control circuitry to a lowest setting; and setting a logic level of the pull-up circuitry to highZ.

12. The system of claim 10, wherein the processor is configured to execute instructions stored in the memory to cause the apparatus to enable the resistance mode, and wherein enabling the resistance mode includes:

setting a logic level of the current shunt circuitry to low; setting a logic level of the voltage/current input scaling circuitry to highZ; setting a duty cycle of the PWM control circuitry to a lowest setting; and setting a logic level of the pull-up circuitry to high.

13. The system of claim 10, wherein the processor is configured to execute instructions stored in the memory to cause the apparatus to enable the voltage mode, and wherein enabling entering the voltage mode includes:

setting a logic level of the current shunt circuitry to low; setting a logic level of the voltage/current input scaling circuitry to low; setting a duty cycle of the PWM control circuitry to a lowest setting; and setting a logic level of the pull-up circuitry to highZ.

14. The system of claim 10, wherein the processor is configured to execute instructions stored in the memory to cause the apparatus to enable the digital/pulse counting mode, and wherein enabling the digital/pulse counting mode includes:

setting a logic level of the current shunt circuitry to low; setting a logic level of the voltage/current input scaling circuitry to low; setting a duty cycle of the PWM control circuitry to a particular percentage based on a determined wetting voltage; and setting a logic level of the pull-up circuitry to highZ.

15. The system of claim 10, wherein the processor is configured to execute instructions stored in the memory to cause the apparatus to enable the analog output mode, and wherein enabling the analog output mode includes:

setting a logic level of the current shunt circuitry to low; setting a logic level of the voltage/current input scaling circuitry to low; setting a duty cycle of the PWM control circuitry to a particular percentage based on an analog output set point; and setting a logic level of the pull-up circuitry to low.

16. The system of claim 10, wherein each of the plurality of modes is enabled using a same terminal of the apparatus.

17. The system of claim **10**, wherein the processor is remote with respect to the apparatus.

18. The system of claim **10**, wherein the system is configured to control one of a refrigeration system and a heating, ventilation, and air conditioning system. 5
